MAGNETIC TAPE PLAYBACK UNIT OR
SIMILAR ARTICLE

David Krechman, 329 S. McCarty Drive,
Beverly Hills, Calif. 90212

Filed Aug. 30, 1965, Ser. No. 86,764

Term of patent 14 years

(Cl. D26—14)

FIG. 1.

FIG. 2.

FIG. 3.

FIGURE 1 is a front top and right side perspective view of a magnetic tape playback unit or similar article showing my new design;

FIGURE 2 is a rear elevational view; and

FIGURE 3 is a side elevational view thereof.

The characteristic features of my new design reside in the combination with conventional tape playing mechanism of a rectangular control panel having parallel ends and parallel top and bottom edges, the bottom edge being wider, with a biplanar front face formed by two surfaces projecting outwardly from a hypothetical vertical plane and meeting below the horizontal center of the face, and knobs projecting outwardly at right angles to the hypothetical vertical plane from the intersecting point of the two surfaces comprising a set of three equally spaced tapered fluted knobs each terminated by a narrow concentric ring of smaller diameter, all as shown.

I claim:

The ornamental design for a magnetic tape playback unit or similar article, as shown and described.
